US0D1084489S

(12) **United States Design Patent** (10) Patent No.: **US D1,084,489 S**
(45) Date of Patent: ** Jul. 15, 2025

(54) **AEROSOL DELIVERY DEVICE**

(71) Applicant: **R.J. Reynolds Tobacco Company**, Winston-Salem, NC (US)

(72) Inventors: **Thaddeus Jude Jackson**, Summerfield, NC (US); **Jared Aller**, Winston-Salem, NC (US); **Billy T. Conner**, Clemmons, NC (US); **Bill Webb**, San Francisco, CA (US); **Chris Harsacky**, San Francisco, CA (US); **Daniel Warren Rennecker**, Naperville, IL (US); **Matthew Joel Nettentstrom**, Bartlett, IL (US); **Steven Michael Schennum**, Plainfield, IL (US)

(73) Assignee: **R.J. Reynolds Tobacco Company**, Winston-Salem, NC (US)

(**) Term: **15 Years**

(21) Appl. No.: **29/782,627**

(22) Filed: **May 7, 2021**

(51) LOC (15) Cl. **27-02**

(52) U.S. Cl.

USPC **D27/162**

(58) **Field of Classification Search**

USPC D27/162, 100, 101, 163–165, 172, D27/174–176, 183, 185–194; D24/110, D24/110.5

CPC A24F 47/002; A24F 47/006; A24F 47/008; A61M 15/00; A61M 15/06

(57) **CLAIM**

The ornamental design for an aerosol delivery device as shown and described.

DESCRIPTION

FIG. 1 is a first perspective view of an aerosol delivery device showing our new design;

FIG. 2 is a second perspective view thereof;

FIG. 3 is a front plan view thereof;

FIG. 4 is a rear plan view thereof;

FIG. 5 is side view thereof;

FIG. 6 is an opposing side view thereof;

FIG. 7 is an end view thereof;

FIG. 8 is an opposing end view thereof;

FIG. 9 is a third perspective view thereof; and,

FIG. 10 is fourth perspective view thereof.

The broken lines shown herein depict subject matter that is included for reference but that forms no part of the claimed design.
